W.M. Chapman Inventor

By *Chas. Snow & Co.* Attorney

UNITED STATES PATENT OFFICE.

WILLIAM MOSES CHAPMAN, OF HARTFORD CITY, INDIANA.

MAIL BOX.

Application filed November 28, 1921. Serial No. 518,358.

To all whom it may concern:

Be it known that I, WILLIAM M. CHAPMAN, a citizen of the United States, residing at Hartford City, in the county of 5 Blackford and State of Indiana, have invented a new and useful Mail Box, of which the following is a specification.

This invention relates to deposit and collection receptacles, and more particularly to 10 deposit and collection receptacles formed with transparent walls, whereby the interior may be viewed through the walls of the receptacle.

The primary object of the invention is 15 to provide a novel form of cover for a deposit and collection receptacle of this type, whereby a person may remove the contents of the receptacle.

A further object of the invention is to 20 provide means for guarding the letter receiving slot of the cover, to prevent rain or moisture from entering the receptacle.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawing:—

Figure 1 is a front elevational view 35 closing a deposit and collection receptacle constructed in accordance with the present invention, and showing a cover as applied.

Figure 2 is a sectional view taken on line 2—2 of Figure 1.

Referring to the drawing in detail, the 40 reference character 5 designates the body portion of the receptacle which is formed preferably of transparent material and formed with a flange 6 at the upper end 45 thereof.

The cover forming the essence of this invention, embodies a depending flange 7 which has its lower extremity turned inwardly as at 8 to position itself behind the 50 flange 6 and prevent removal of the cover.

Formed integral with the flange 7, and disposed at the rear thereof are the up-

wardly extending ears 9 which are formed with tubular portions 10 adapted to accommodate a pin for securing the protector 11 to the body portion or flange 7.

The protector 11 is also formed with flanges 12 extending downwardly from the sides thereof, which flanges embrace the pivoted closure member 13 to prevent moisture from entering the member 13 from the sides. The member 13 is formed with a slot 14 whereby articles may be inserted in the receptacle. Formed at the rear of the member 13 are upwardly extending ears 15, 65 which have tubular portions 16 adapted to embrace the pin 17 which provides a part of the hinge between the pivoted sections of the cover.

Secured to the forward portion of the 70 member 13 is a hasp 18, which hasp is formed with an opening to receive the staple 19 which is designed to accommodate a suitable padlock to prevent unauthorized persons from gaining access to the interior 75 of the receptacle. The hasp is relatively long, and has the lower portion thereof bent upwardly as at 19' to provide a paper holder, whereby papers or relatively large articles may be hung on the mail box.

Secured to the under surface of the 80 protector 11, is a card support indicated at 20, whereby the owner of the receptacle may place his card therein to facilitate the delivery of mail.

Having thus described the invention, what is claimed as new is:—

A cover for deposit and collection receptacles including a body portion comprising 90 a depending flange, a hinged closure having a receiving slot, upwardly extending ears forming a part of the hinged closure, a protector hingedly connected to the closure, a hasp forming a part of the closure, a staple carried by the body portion and adapted to 95 pass through the hasp and receive a padlock for securing the closure in a closed position.

In testimony that I claim the foregoing as my own, I have hereto affixed my signature in the presence of two witnesses.

WILLIAM MOSES CHAPMAN.

Witnesses:

ETHAN W. SECREST,
EARL REASONER.
